Filed Mar. 4, 1963, Ser. No. 262,414

10 Claims. (Cl. 214—1)

This invention relates to a repeating cycle article transfer and loading mechanism.

While not limited thereto the mechanism of the present invention is particularly well suited for laterally transferring and alining stacked articles, such as newspapers and the like, from a stacking machine to a position in registration with top entry opening in a stack wrapping machine, and then positively moving them downwardly against a precut length of wrap material, and together with the latter, into the bottom of a wrapping machine.

A machine is presently available for providing an overlapped and glued band wrap of paper around four sides of each one of successive stacks of newspapers which are fed into it. As originally designed this wrapping machine contemplated that alined stacks of newspapers would be stacked at a point above a top entry opening into the machine and then dropped under gravity into such opening. However, the only presently successful high speed stackers for newspapers and the like provide lateral or side discharge of stacks of newspapers. In order to properly mate this wrapping machine to such stackers a suitable transfer and loading mechanism must be provided.

In the aforementioned wrapping machine the stacks of newspapers in dropping thereinto under gravity engage a precut length of wrap material, and, with the latter, then drop on down to the bottom of the machine preparatory to the compression and succeeding wrap folding and gluing cycles. It has been found that use of gravity force alone to accomplish this loading of the stack with its length of wrap leaves much to be desired in respect of consistency of the time interval required. The use of additional force to positively drive the stack down into the top entry opening of the machine into engagement with the length of wrap, and, with the latter, to the bottom of the machine makes for much better consistency in the time interval required, in repetitive operation.

It is therefore a primary object of the present invention to provide an article transfer and loading mechanism to carry out the aforementioned desirable functions.

Another object is to provide a mechanism of the aforementioned type which comprises a transfer unit for effecting lateral transport of stacked articles between first and second points, gates at the second point for temporarily holding the articles, and a ram for positively moving the stack of articles downwardly to another point below the second point following opening of the gates.

A further object is to provide a control system for the aforementioned mechanism to automatically afford operation of the same as demanded by the presence of, and intervals between articles being delivered to the first point.

Other objects and advantages of the invention will hereinafter appear.

The accompanying drawings illustrate a preferred embodiment of the invention which will now be described in detail, it being understood that the embodiment illustrated is susceptible of various modifications without departing from the scope of the appended claims.

In the drawings:

FIGURE 1 is a perspective view of an article stacker wrapper mechanism which incorporates my invention.

FIG. 2 is a fragmentary view in side elevation of a portion of such mechanism to enlarged scale taken along the line 2—2 of FIG. 1.

2

FIG. 3 is a perspective view of a stack transfer unit in an initial operating position.

FIG. 4 is a view like FIG. 3 but showing the stack transfer unit in another operating position.

5 FIG. 5 is a view like FIGS. 3 and 4 but showing the stack transfer unit in still another operating position.

FIG. 6 is a view taken along the line 6—6 of FIG. 1 showing another portion of the mechanism in an initial operating position.

10 FIG. 7 is a fragmentary view like FIG. 6 but showing the same portion of the mechanism in another operating position.

FIG. 8 is a view like FIGS. 6 and 7, but showing the same mechanism in still another operating position.

15 FIG. 9 is a diagrammatic view of a control system for the portions of the stacker and wrapper mechanism shown in FIGS. 2 to 8.

FIG. 10 is a more or less schematic view of the transfer unit, the pneumatic operator therefor and certain 20 control devices associated therewith.

FIG. 11 is a more or less schematic view of a ram, a pneumatic operator therefor and certain control devices associated therewith, and

25 FIG. 12 is a more or less schematic view of gates, a pneumatic operator therefor and certain control devices associated therewith.

FIG. 1 shows a complete stacker-wrapper mechanism for newspapers and the like which comprises a stacker unit 14, a transfer unit 16, a loading unit 18, a stack wrapper unit 20 and wrapped stack run out conveyor 22. 30 Stack unit 14 in one preferred form is like that described in the Howdle et al. Patent No. 2,819,661 now Reissue Patent No. 25,018 and may be assumed to deliver vertically stacked and alined newspapers at its right hand side.

35 The stack wrapper unit 20 is of a commercially available type wherein stacks of newspapers are fed at regular intervals to the top entry opening and then released to drop under gravity into engagement with a precut length of wrap material to the bottom of a rectangular trough formed by a stationary bottom plate and the adjacent sides of side wall conveyors. The wrap adjacent its upper ends are then gripped and the stack is then advanced in steps through a compression zone. The wrap ends are then released and the compressed stack advances 40 through a flap folding and gluing zone and then discharged to a run-out conveyor or the like. The stack wrapper unit 20 per se does not form part of the present invention and only parts thereof necessary to an understanding of the present invention will be described in detail.

45 Transfer unit 16, which is best shown in FIGS. 2 to 5 and 11, has a carriage 17 comprising a rectangular frame or yoke 24 having a top member 24a, vertical side members 24b and 24c, and bottom stub members 24d and 24e. Parallel, horizontal stack support blades 26 and 28 are mounted on each of the stub members 24d and 24e, respectively, in spaced apart relation on opposite sides of an endless belt conveyor 30 which extends from the delivery end of stacker unit 14 and the entrance to loading unit 18. Blades 26 and 28 have horizontal flat portions which at their outer edges join at a right angle with downwardly turned flanges which lie adjacent the sides of conveyor 30.

50 Carriage 17 is mounted for reciprocating movement on horizontal guide rods 32 and 34 by means of longitudinally bored guide blocks 36 and 38 which are secured to the upper surface of member 24a. Rods 32 and 34 are supported at corresponding ends to a stationary frame member 40 on which is also mounted a linear acting pneumatic piston operator 42. Cylinder 42a is mounted on one side of member 40, and has piston rod 42b which

extends through a clearance opening in member 40 and connects through a pin and clevis connector 44 to a block 46 secured to members 24a midway between slide blocks 36 and 38.

The carriage has two stack pusher members 48 and 50 which are pivotally mounted at their upper ends adjacent members 24b and 24c, on member 24a, and at their lower ends on stub members 24c and 24d respectively. The upper pivot pins 48a and 50a of members 48 and 50 extend through members 24a and cam follower operating arms 52 and 54 are non-rotatably fixed on pins 48a and 50a. Tension springs 48b and 50b are attached at corresponding ends to pins 48c and 50c on the upper edges of members 48 and 50, respectively, and are attached at their other ends to pins 24f and 24g, respectively, fixed on member 24a. When the carriage is in the position depicted in FIG. 3 the rollers 52a and 54a on the ends of arms 52 and 54 engage with the cam surfaces 56a and 56b of a cam member 56 (see FIG. 10), which is stationarily mounted in stacker unit 14 near its delivery end, to hold the members 48 and 50 in "open" or "non-pushing" position against the bias of the springs 48b and 50b. When the carriage is moved to the right, rollers 52 and 54 disengage from cam surfaces 56a and 56b, and pusher members 48 and 50 move under the bias of springs 48b and 50b to the positions depicted in FIG. 4. Engagement of pins (not shown) with stop members (not shown) secured to the lower surface of member 24a, and engagement of similar pins (not shown) secured to the lower edges of members 48 and 50 respectively with the outer edge of the blades 26 and 28, determine the last mentioned position for members 48 and 50. Such position is termed the "closed" or "pushing" position.

Stationary vertical plates 58 and 60, which in one preferred form are formed of a transparent plastic material, are spaced apart from carrier members 26 and 28, and extend from the entering end of the loading unit 18 to a point slightly to the left of the leading edges of pusher members 48 and 50 when the carriage 17 is in its starting position (see FIG. 2). Plates 58 and 60 provide side wall enclosures for the transfer unit, and prevent papers spilling off to either side.

FIG. 10 shows carriage 17 together with pneumatic operator 42, valves and limit switches used to control such operator. Slide valves SV1 and SV2 are provided to control the admission and exhaustion of air under pressure to and from the interior of the cylinder 42a on opposite sides of the piston 42c. Electroresponsive solenoids SOL1 and SOL2 are provided to move valve SV1 between left and right-hand operating positions. Valve SV2 is spring biased to a left-hand operating position and is movable against such bias to a right-hand operating position whenever its electroresponsive solenoid SOL3 is energized.

Valve SV1 when in its left-hand position depicted in FIG. 10 has its right-hand passageway positioned to admit air from a high pressure air conduit 62 into a conduit 64, which is connected to the interior of the cylinder 42a on the right-hand side of piston 42c. The center passage-way is then connected to vent air to atmosphere from a conduit 66 which is connected to corresponding ends of parallel conduits 68, 70 and 72. Conduits 68, 70 and 72 are connected at their other ends to a conduit 74 that is connected to the interior of the cylinder 42a at the left-hand side of piston 42c. Valve SV2 is interposed in conduit 68 and closes such conduit when in its left-hand extreme position depicted. A throttling valve 76 is interposed in conduit 70 and may be assumed to throttle air flow in either direction through such conduit. A one-way check valve 78 is interposed on conduit 72 and permits free flow of air through the latter in the direction of the arrow while preventing flow in the reverse direction.

Solenoid SOL1 is controlled by a limit switch LS1 (see FIGS. 9 and 10), and solenoid SOL2 is controlled

5 by a limit switch LS2. Solenoid SOL3 is controlled by a limit switch LS3. Limit switches LS4 and LS5 shown in FIG. 10, together with those just mentioned, will be hereafter described more fully in conjunction with the complete electrical control circuit of FIG. 9.

10 Loading unit 18 is positioned over the top entry opening to the stack wrapper unit 20. It comprises a pair of pivotally supported gates 80 and 82 which are operable by a pneumatic piston operator 84 (see FIG. 12) between a "closed" or stack "hold" position, and an "open" or stack "drop" position. Unit 18 further comprises a vertically movable ram 86 which is moved by connecting rod 88c of a pneumatic piston operator 88.

15 The gates 80 and 82 are non-rotatably supported across their upper ends on rods 90, which at their left-hand ends as viewed in FIGS. 1 and 2, are journaled in vertical support members 92 and 94. Their right-hand ends, rods 90, are journaled to vertical support members 96 and 98, respectively. A pair of inverted L-shaped brackets 100 and 102, which at their left hand ends are secured to vertical support members 92 and 94 respectively, have a plate 103 secured to their horizontal legs on which is mounted pneumatic operator 88. The other ends of the brackets 100 and 102 are secured to vertical support members 96 and 98, respectively. Longitudinally extending horizontal support members 114 and 116 have an inverted, substantially V-shaped yoke 118, secured thereto and the latter carries a pillow block 120 for support of the right-hand end of pneumatic operator 42. Upper side guide plates 122 and 124 are secured to their left-hand ends to the vertical support members 92 and 94, and at their right-hand ends to vertical support members 96 and 98 respectively. A vertical back plate 130 secured to members 96 and 98 together with side plates 122 and 124, define the outer limits of a centering trough for the incoming stacks of newspapers on gates 80 and 82 and over the top entry opening the stack wrapper. Side plates 122 and 124 are spaced apart a distance slightly greater than the width of the articles and less than the spacing between plates 58 and 60. Plates 58 and 60 are connected by angle plates 104 and 106 to plates 122 and 124, respectively.

20 Ram 86 has a rod 132 secured thereto and the enlarged cam head 132a thereof in a lower limit position engages with the operating arm of a limit switch LS6 to (see FIG. 11) initiate a control operation as will hereafter be more fully described.

25 As best shown in FIG. 12 piston 84b of operator 84 is pivotally connected through its piston rod 84c to a lever plate 134 which at one corner is non-rotatably fixed on the pivot rod 90 at gate 82. A lever arm 136 is non-rotatably fixed on rod 90 of gate 80, and has pivotal connection with one end of a connecting rod 138 which at its other end has pivotal connection with lever plate 134. An arm 140 fixed on rod 90 of gate 82 effects closure of limit switch LS1 when gate 82 attains "closed" or stack "hold" position.

30 A slide valve SV3, is operable between the left-hand and right-hand positions by solenoids SOL4 and SOL5. In its left-hand position depicted in FIG. 12 its right passage connects air supply conduit 62 to a conduit 142 that connects interiorally of the cylinder 84a of operator 84 on the right-hand side of piston 84b. The central passageway of valve SV3 in the last mentioned position of the valve connects a conduit 144, having connection with the interior of cylinder 84a to the left of piston 84b to the atmosphere. When solenoid SOL5 is energized, as will hereafter be explained, a slide valve SV3 is moved to its right-hand position wherein its left-hand passageway connects conduit 144 to conduit 62 to supply high pressure air to the left-hand side of piston 84b to effect drive of the latter and piston rod 84c to the right. As a result lever plate 134 and gate 82 will pivot counterclockwise, and gate 80 through its con-

nection with lever plate 134 by lever 136 and rod 138 will simultaneously be pivoted clockwise.

Gates 80 and 82 are provided with tabs 80a and 82a, respectively, adjacent their edges nearest the stacker unit, which when the gates are "closed" and carriage is returned to its initial position at the stacker unit, holds the stacks in place on the gates against withdrawal with return of the carriage. This action will hereinafter be more fully explained.

Operation of the stack transfer unit 16 and loading unit 18 will now be described. Stack unit 14 may be assumed to be driven in synchronism with a newspaper printing press folder and an input conveyor (not shown). It further may be assumed to deliver aligned stacks of newspapers of predetermined numbers to the left-hand end of conveyor 30 at regular intervals determined by the speed of the press folder and of the stacker input conveyor.

At the start of a "run" the transfer unit carriage will be in the position down in FIGS. 2, 3 and 10. Conveyor 30 is driven by, and in synchronism with, the stacker. As a stack of newspapers SP is carried by conveyor through yoke 24 portions of the bottom paper bear and slide on the upper surfaces of the carriage blades 26 and 28. As the stack SP continues to advance its forward end operates limit switch LS2 (see FIGS. 9 and 10) which completes an energizing circuit for solenoid SOL2 to operate valve SV1 to its right-hand position. Valve SV1 in its right-hand position admits high pressure air from conduit 62 through conduits 66, 70 and 72 throttling valve 76 and check valve 78, and conduit 74 into cylinder 42a on the left-hand side of piston 42c. Simultaneously the center passage in valve SV1 connects the interior of cylinder 42a, on the right-hand side of piston 42c, through conduit 64 to the atmosphere. Consequently piston 42a, and hence, carriage 17 are driven rapidly to the right.

As the carriage moves out of its starting position the rollers on the cam followers 52 and 54 disengage from the cam 56 and pusher members 48 and 50 move to their positions shown in FIG. 4 wherein they engage with the rear end of the stack SP. The stack SP resting on the blades 26 and 28 over a considerable portion of the bottom paper, and engaged from its rear end by pusher members 48 and 50, is quickly advanced to the right to the position depicted in FIG. 5 at a speed somewhat greater than the linear speed of the belt of conveyor 30. In this position the stack is then centered over the top entry opening in stack wrapper unit 20.

As stack SP moves into the last mentioned position a pad 24K on yoke 24 engages the operator of limit switch LS4 (see FIGS. 10 and 11) to close the latter. As seen in FIG. 12, closure of limit switch LS4 results in energization of solenoid SOL5 to move valve SV3 to its right-hand position wherein operator 84 is energized appropriately with high pressure air to effect operation of gates 80 and 82 to "closed" or stack "hold" position beneath the carriage blades 26 and 28.

Arm 140 engages the operator of limit switch LS1 as gate 82 moves into its last mentioned position to open its contacts LS1A and close its contacts LS1B. Closure of contacts LS1B results in energization of solenoid SOL1. As a result valve SV1 is returned to its left-hand position depicted in FIG. 10, and as will be understood, operator 42 drives the carriage of the transfer unit to the left toward its starting position in the stacker unit. Air being exhausted from cylinder 42a on the left hand side of piston 42b must pass through conduits 68 and 70 and valves SV2 and 76 interposed therein, as check valve 78 is then closed.

As the carriage nears its starting position an arm 36a secured to slide block 36 re-engages the operator of limit switch LS3 to open the latter. This results in deenergization of solenoid SOL3 and return of valve SV2 to its position shown in FIG. 10 wherein it blocks

passage of air through conduit 68. Thus any remaining air to the left of piston 42c must then pass through conduit 70 and throttling valve 76 to atmosphere. Consequently venting is markedly slowed down to provide air "cushioning" as piston 42c approaches the left-hand limit of its travel. This prevents the carriage abruptly "slamming" into its starting position thereby enhancing mechanical life of the carriage and associated parts.

On carriage 17, leaving its final position depicted in FIGS. 5 and 6, and moving to the left as last described, stack SP is retained in its position over the top entry opening to the stacker by the side tabs 80a and 82a (see FIGS. 5 and 7) engaging with the rear end of the stack at the blades 26 and 28 of the carriage slide out from engagement with the bottom paper of the stack. The stack SP then drops onto the lower arms of gates 80 and 82.

The carriage on return to the left disengages from the operator of limit switch LS4 to permit the latter to reopen and deenergize solenoid SOL5. As the carriage approaches its starting position and arm 36a secured to slide block 38 engages the arm 150a of a lever 150 pivotally mounted on cam 56 and effects counter-clockwise pivotal movement of lever 150. Lever 150 in pivoting engages its other arm 150b with the operator of limit switch LS5 to momentarily open the latter to close its contacts LS5A and open its contacts LS5B, followed by reopening of contacts LS5A and re-closure of contacts LS5B as arm 36a passes beyond the 30 arm 150a of lever 150.

As will be seen from FIGS. 9, 11 and 12 momentary closure of contacts LS5A results from momentary energization of solenoids SOL4 and SOL6. Due to the prior deenergization of solenoid SOL5 by the opening of limit switch LS4, energization of solenoid SOL4 results in movement of air valve SV3 to its left-hand position depicted in FIG. 12 wherein air is admitted appropriately into the cylinder operator 84 to effect opening of gates 80 and 82. The simultaneous momentary reenergization 40 of solenoid SOL6 results in movement of air valve SV4 to its left-hand position wherein it admits air from high pressure air conduit 62 through conduit 146 to the interior of cylinder 88a of operator 88 above piston 88b to drive the latter, and hence ram 86 downwardly against the uppermost paper of stack SP.

With gates 80 and 82 open and ram 86 engaging the stack SP the latter is positively driven downwardly against a sheet of pre-cut wrap paper 164 (see FIG. 8) and together with the bottom stationary plate 166 of stack 50 wrapper unit 20 between sidewall conveyors 168 and 170 thereof.

When ram 86 reaches its lower position the cam end 132a on rod 132 engages with the operator of limit switch LS6 to close the latter (see FIGS. 6 and 11). Closure of the latter then completes a circuit through the then closed contacts LS5B of limit switch LS5 to energize solenoid SOL7. As solenoid SOL6 has only momentarily energized, to drive valve SV4 to its left-hand position, energization of solenoid SOL7 results in return of valve SV4 to its position shown in FIG. 12 wherein air is exhausted from above piston 88b to atmosphere through conduit 146, and high pressure air is admitted to cylinder 88a below piston 88b through conduit 148 to drive ram 86 upwardly to its starting position to complete the cycle of operation of transfer loading mechanism.

The control system depicted in FIG. 9 is a somewhat modified portion of a more comprehensive continued system for a complete stacker-wrapper mechanism disclosed and claimed in the Frank S. Hyer application Serial No. 262,428 filed March 4, 1963.

I claim:

1. In an article transfer mechanism, in combination, a carriage movable between first and second points and comprising parallel article support members spaced apart

transversely of its axis of movement and means for supporting said carriage for reciprocal movement, a conveyor having an article carrying run in proximate coplanar alignment with the article carrying surfaces of said support members, said conveyor being positioned between and running along the axis of movement of the carriage support members with its entering end at a third point in line with and ahead of said first and second points to convey articles onto said support members, and means including means responsive to advance of articles by said conveyor to a given position on said support members to move said carriage and any articles thereon to said second point.

2. The combination according to claim 1, together with means at said second point operable when said carriage is moved back to said first point to prevent withdrawal of said articles with the latter and to hold them at a fourth point below said second point.

3. The combination according to claim 2, wherein the last recited means comprises a pair of gates having first portions which when operated as aforesaid are interposed behind said articles when the carriage reaches said second point and having portions onto which said articles drop when the carriage returns to said first point.

4. The combination according to claim 3, together with a ram normally positioned above said second and fourth points and means for moving said ram downwardly to a fifth point, whenever said gates are reversely operated to remove support from under articles at said fourth point, to drive the articles through said fifth point.

5. The combination according to claim 4, wherein said carriage, said gates, and said ram are provided with fluid power operators individual thereto and wherein control means under the direction and control of limit switches provide sequential energization of said operators to afford the movement of said carriage, said gates and said ram as aforesaid.

6. The combination according to claim 1, wherein said carriage comprises a yoke carrying said article support members and pusher members pivotally mounted on said yoke on opposite sides of said conveyor, said pusher members when said carriage is at said first point being held substantially parallel to the sides of the conveyor and said pusher members having bias such that when said carriage is not in said first position they angle inwardly toward the center line of the conveyor to engage their leading ends against articles that may be on said support members so that any relative movement between said carriage in its movement toward said second point and the conveyor will not displace the articles on the support members.

7. The combination according to claim 3, wherein said gates are oppositely disposed, of L-shaped configuration, and have tabs projecting transversely of the center line of the conveyor which in closed position of the gates project behind any articles on the carriage so upon return of the latter to said first point any such articles are prevented from moving with the carriage, which upon such return, then slides out from under said article to drop them onto the lower arms of said gates.

8. The combination according to claim 6, wherein said yoke is of inverted U-shaped form with portions extending inwardly towards the conveyor and wherein said support members are secured to said portions and have upper surfaces parallel with but slightly below the plane of the conveyor.

9. In an article transfer mechanism, in combination, a carriage, means comprising a fluid power operator energizable to move said carriage between first and second points, said carriage having parallel article support members spaced apart transversely of its axis of movement, a belt conveyor having an upper belt run positioned between the carriage support members and having its entering end at a third point ahead of said first point to convey articles onto said support member, a pair of gates disposed on opposite sides of said second point, which when closed, have arms positioned to hold articles at a fourth point below said second point, and have tabs interposed behind articles carried by said carriage to said second point to prevent their withdrawal with said carriage when it returns to said first point, second means including fluid power responsive means energizable to move said gates between said closed position and an open position to drop any articles previously on said arms, and control means including a first switch operable by articles moving on said belt run to a given position relative to said carriage when the latter is at said first point to energize the operator of the first mentioned means to move said carriage to said second point, a second switch operable by said carriage when it reaches said second point to energize the operator of said second means to close said gates and to reversely energize the operator of the first mentioned means to move said carriage back to said first point, and a third switch operable by said carriage as it approaches said first point to reversely energize the operator of said secured means to open said gates.

10. The combination according to claim 9 together with a ram normally positioned above said second and fourth points, a fluid power operator energizable to move said ram downwardly through said second and fourth points to a fifth point therebelow, and means included in said control means responsive to the aforementioned operation of said third switch to energize the last mentioned operator as aforesaid.
